UNITED STATES PATENT OFFICE.

JOHN REECE, OF ST. LOUIS, MISSOURI, ASSIGNOR TO EVR-KLEAN SEAT PAD CO., OF ST. LOUIS, MISSOURI, A CORPORATION OF MISSOURI.

SEAT COVER.

Application filed March 13, 1922. Serial No. 543,298.

To all whom it may concern:

Be it known that I, JOHN REECE, a citizen of the United States, residing at St. Louis, Missouri, have invented a new and useful 5

5 Seat Cover, of which the following is a specification.

This invention relates to seat covers.

An object of the invention is to provide an improved seat cover composed of pivotally united seat and back members characterized by sufficient flexibility to conform 10 properly to the contour of the support on which they are placed, and by sufficient stiffness so that the back member will stand upright without folding or crumpling, and having a cover, such as cloth or the like, on their back sides so that they will not chafe or mar the seat on which the device is placed.

20 Another object of the invention is to provide an improved seat cover embodying the subject-matter mentioned, and having means for securing the seat member thereto in connection with the support.

25 Another object of the invention is to provide an improved seat cover having a drop pivotally united to the forward edge of the seat member that will fold or bend readily transversely so that the device will fit upon 30 seats of different widths.

Another object of the invention is to provide a seat cover in which the drop may be folded under the seat member when it is not desired to make use of the drop.

35 Another object of the invention is to provide an improved seat cover composed of straw matting, and comprising seat and back members in which the warp straws extend from the forward to the rear edge of

40 the seat member and from the lower edge to the upper edge of the back member, and in which the woof straws extend transversely; in combination with a drop composed of straw matting having the warp straws 45 extending transversely so as to make the drop more readily foldable and more readily flexible transversely in order to bend and conform to the edge of the seat.

50 Other objects will appear from the following description, reference being made to the drawing, in which—

Fig. 1 is an open plan view of the seat cover.

Fig. 2 is an inverted plan view.

Fig. 3 is a sectional view on the line 3—3 of Fig. 1.

Fig. 4 is a sectional view on the line 4—4 of Fig. 1.

The upper layer 1 of the back member is composed of straw matting having the warp straws thereof extending from the forward to the lower edge and the woof straws running transversely; in combination with a piece 2 of canvas or the like secured to and covering the entire rear side of the section 60 of matting. If desired, one side edge of the canvas may be left detached from the straw matting to permit the insertion of a cushion. The vertical side edges of the upper or forward side of the matting are provided with 65 a relatively wide reinforcement 3 of cloth or the like secured thereto by a line of stitching 4 passing through the matting and the canvas 2. The entire border of the back member is enclosed within a reinforcing 70 strip 5 of canvas, or the like, secured thereto by a line of stitching 6 passing through the part 5 and through the interposed straw matting back 2 and reinforcement 3.

The seat member is composed of an upper 75 layer of straw matting 7 having the warp straws extending from the forward to the rear edge and the woof straws running transversely. To the under side of the straw matting 7 a protecting cover 8 of 80 canvas, or the like, is secured, and if desired, one edge may be left separate to permit the insertion of a cushion between the matting and the canvas. The lateral side edges of the matting are covered by reinforcing strips 9 of canvas secured thereto by stitching 10. A reinforcing border 11 of canvas encloses the entire marginal edge of the seat member and is secured thereto by stitching 12.

The back and seat members are pivotally 85 united by stitching 13 that will permit the back and seat members to be folded flat against each other.

A drop is secured to the forward edge 100 of the seat member and is composed of straw matting 14 having the warp straws running transversely and the woof straws extending from the upper to the lower edge. The underside of the drop comprises a piece 105 of canvas 15 and the entire marginal edge of the drop is enclosed in a protecting border 16 of canvas. Intersecting lines of

stitching 17 secure the pieces of matting 14 and the canvas 15 together. The drop is pivotally united to the seat member by a line of stitching 18 that will permit the drop to be folded under the seat member if desired.

Across the corners of the seat and back members lines of stitching 19 are placed to obtain a better connection between the 10 parts. The diagonal lines of stitching 19 are especially desirable if one of the side edges of the canvas is left disconnected.

The seat member has a number of flexible loops 20 secured to the under side there- 15 of for engagement with parts of the seat or with binding devices when it is desired to secure the seat member to the seat.

From the foregoing it will be seen that my invention obtains all of its intended 20 objects and purposes, and will not chafe or mar the finished surface of a seat to which the device is applied. Having the woof threads running in the direction stated better results are obtained in that the device 25 will conform perfectly to the shape of the seat on which the cover is applied.

I do not restrict myself unessentially, but what I claim and desire to secure by Letters Patent is:—

30 1. A seat cover, comprising back and seat members, whose exposed surfaces are composed of straw matting and whose back surfaces are composed of cloth, a marginal reinforcement around each of said members, 35 a pivot connection uniting said members

permitting one to be folded flat against the other, and a drop pivotally united to the forward edge of the seat member and having the warp straws thereof extending laterally.

2. A seat cover, comprising back and seat members, whose exposed surfaces are composed of straw matting and whose back surfaces are composed of cloth, a marginal reinforcement around each of said members, 40 a pivot connection uniting said members permitting one to be folded flat against the other, a drop pivotally united to the forward edge of the seat member and having the warp straws thereof extending laterally 45 transversely of the warp straws of the seat and back members, and a cloth border enclosing the marginal edge of the drop.

3. A seat cover, comprising back and seat members, whose exposed surfaces are composed of straw matting and whose back surfaces are composed of cloth, a marginal reinforcement around each of said members, a pivot connection uniting said members 50 permitting one to be folded flat against the other, a drop pivotally united to the forward edge of the seat member and having the warp straws thereof extending laterally 55 transversely of the warp straws of the seat and back members, a cloth border enclosing the marginal edge of the drop, 60 and a canvas back covering the underside of the drop and secured thereto by stitching.

JOHN REECE.
